UNITED STATES PATENT OFFICE.

THOMAS D. MATHENY, OF PONTIAC, MICHIGAN.

LIFEBOAT AND DIVING APPARATUS.

1,331,819.

Specification of Letters Patent. Patented Feb. 24, 1920.

Application filed October 21, 1919. Serial No. 332,263.

To all whom it may concern:

Be it known that I, THOMAS D. MATHENY, a citizen of the United States, residing at Pontiac, in the county of Oakland and State of Michigan, have invented certain new and useful Improvements in Lifeboat and Diving Apparatus, of which the following is a specification, reference being had to the accompanying drawings.

10 This invention relates to an improved life boat and diving apparatus and it is an object of the invention to provide a novel and improved device of this general character wherein the motor for propelling the 15 boat may be employed to charge air tanks to give buoyancy to the boat and to supply the diver, when submerged, with necessary air.

It is also an object of the invention to 20 provide a novel and improved device of this general character whereby the air may be delivered to the diver directly from the compressor or pump, or from a tank containing air under pressure.

25 An additional object of the invention is to provide a novel and improved device of this general character including a propeller rotatably supported by and below the boat, and which operates to maintain the boat in desired position with respect to the diver when submerged.

Figure 1 is a view partly in elevation and partly in section and of a diagrammatic character illustrating a device constructed in accordance with an embodiment of my invention;

Fig. 2 is a view in rear elevation of the boat, as herein disclosed;

Fig. 3 is a sectional view taken substantially on the line 3—3 of Fig. 1;

Fig. 4 is a fragmentary view in side elevation of a reel, as herein embodied, and which coacts with a line leading from the diver;

45 Fig. 5 is a fragmentary sectional view taken through the reel illustrated in Fig. 4, and illustrating the manner of winding thereon, and,

50 Fig. 6 is a fragmentary view partly in section and partly in elevation, of a reel

around which an air line is adapted to be wound.

As disclosed in the accompanying drawings, B denotes a boat of desired dimension and configuration, and which is adapted to be propelled through the medium of the propeller P, carried by a driven shaft 1. The shaft 1 coacts with the driving shaft 2, driven by a motor M, preferably of an internal combustion type, and the connection between the shafts 1 and 2, as illustrated in Fig. 1, is through the instrumentality of the movable clutch member 3 under the control of an operating lever 4.

The fore portion of the boat at opposite sides of its transverse center or keel is provided with the tanks T adapted to contain air under pressure, in order to increase the buoyancy of the boat B. The tanks T are connected by the transversely disposed 70 pipe 5, having interposed therein a controlling valve 6. The rear portion of the boat at its opposite sides is provided with the exteriorly arranged tanks T', also adapted to contain air under pressure, and to further increase the buoyancy of the boat.

C denotes an air compressor or pump driven from the shaft 2, and leading from the compressor or pump C to one of the tanks T is a pipe line 7. Interposed in the 80 pipe line 7 is a controlling valve 8. Rotatably supported by a side of the boat is a pair of reels R, about each of which is adapted to be wound an end portion of an air line or hose 9 leading to the helmet H 85 of a diver's armor, and interposed in said line or hose immediately adjacent the helmet H is a controlling valve 10.

One end portion of the line or hose 9 is in communication with the hollow shaft 11 90 of a reel R, and leading from the shaft 11 of one of the reels R is a pipe line 12 in communication with the pipe line 7 exteriorly of the tank T, and in advance of the controlling valve 6. Interposed in the 95 line 12 is a controlling valve 14 and a check valve 15, said check valve 15 preventing retrograde flow through the line 12.

A hollow shaft 11 of the second reel R has in communication therewith a pipe line 100

16 leading to a tank T, and interposed in the tank T is a controlling valve 17.

Extending through the bottom of the boat B is a shaft 18, having its upper end portion operatively engaged, as at 19, with the shaft 2, and which connection is under control of the members 20, one of which is slidably operated by the lever 21 within the boat B.

G denotes a guard inclosing the lower or extended portion of the shaft 2 and comprising two relatively movable sections. The lower section 22 affords a bearing for an end portion of a shaft 23, having universal connection, as at 24, with the lower portion of the shaft 18, whereby the shaft 23 is permitted to have swinging movement. Fixed to the shaft 23 is a propeller 25.

The requisite relative movement of the sections of the guard G is permitted in view of the fact that the lower section of said guard has a greater radius than the upper section and whereby angular or swinging movement of the shaft 23 with relation to the shaft 18 is possible.

Secured to the lower section 22 of the guard G and at a point substantially in longitudinal alinement with the shaft 23 is an end portion of a flexible member 26. The member 26 leads to and is secured to the shaft 27 of a reel R'. The reel R' is adapted to be secured through the medium of a suitable harness 28 to the shoulder of the diver, as is indicated in Fig. 1.

The reel R' includes the radial side arms 29 and a pair of arms 29, alined longitudinally of the shaft 27, Fig. 5, are provided with the openings 30, spaced longitudinally of said arms 29, and through which the pins 31 are adapted to be inserted. The flexible member 26 can be readily lengthened with respect to the reel, as the diver submerges by removing a pin 31, as the occasions of practice may require. In rolling the member 26 upon the reel R' it is preferred that four wrappings be made around a pin 31, before a second pin is applied.

As the diver moves about when submerged, the flexible member 26 will cause the shaft 23 to move in a direction to extend longitudinally toward the diver, and the pitch of the propeller 25 is such that the boat will be caused to follow the diver, it being understood that while the diver is submerged, the propeller 25 is in operation and the propeller P is inoperative. When the member 26 becomes slack, the shaft 23 will assume substantially a vertical position whereby the continued rotation of the propeller 25 will not cause the boat to recede from the diver. Propeller 25 causes the boat to be maintained substantially directly above the diver when submerged and causes the boat to follow the diver as he moves about below the surface of the water. In view of this the feeding of air to the diver is ma-

terially facilitated, and also assures the boat to be maintained at all times in such proximity to the diver to facilitate his return to the surface, as it is unnecessary for the diver to travel in submergence any decided distance in order to position himself to be returned to the surface.

It will also be understood that air may be delivered to the diver when submerged, directly from the compressor or pump C, or, as in the case of an emergency, air may be conveyed to the diver directly from a tank T.

The valve 10 in each of the lines 9 permits the diver to control the admission of air within the helmet H, as best meets the requirements of practice, while the valves 6, 8, 14 and 17 are adapted to be opened, closed or otherwise adjusted as necessities may require.

A pair of the opposite arms of each of the reels R is provided with registering apertures or openings 30^a, to receive the pins 31^a, similar to those of the reel R', to prevent the pipe line from unreeling too rapidly.

From the foregoing description, it is thought to be obvious that a life boat and diving apparatus constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the character described comprising a boat, a shaft extending exteriorly of the boat, means for operating the shaft, a second shaft in operative engagement with the first named shaft and having swinging movement relative thereto, a propeller carried by said second shaft, and means for imparting swinging movement to the second shaft and adapted for connection with an object in submergence.

2. A device of the class described comprising a boat, a shaft extending exteriorly thereof, means for rotating the shaft, a guard surrounding the exterior portion of the shaft, said guard comprising relatively movable sections, a second shaft operatively engaged with the first named shaft and having swinging movement relative thereto, one of the sections of the guard serving as a bearing for the second shaft, a member engaged with said section of the guard and adapted for connection with an object in submergence, and a propeller carried by said second shaft.

3. A device of the character described

105

115

130

comprising a boat, a shaft extending exteriorly of the boat, means for operating the shaft, a second shaft in operative connection with the first named shaft and having swinging movement relative thereto, a propeller carried by said second shaft, and flexible means for imparting swinging movement to the second shaft and adapted for connection with an object in submergence, and a winding medium coacting with said flexible member.

In testimony whereof I hereunto affix my signature.

THOS. D. MATHENY.
